Primary Examiner—Wallace R. Burke*Assistant Examiner*—Melody N. Brown*Attorney, Agent, or Firm*—Litman, McMahon & Brown**[57]****CLAIM**

The ornamental design for an all terrain vehicle cab, as shown and described.

DESCRIPTION

FIG. 1 is a perspective view of an all terrain vehicle cab showing my new design;

FIG. 2 is a side elevational view of the cab, with the opposite side being a mirror image thereof;

FIG. 3 is a rear elevational view of the cab;

FIG. 4 is a front elevational view of the cab;

FIG. 5 is a bottom plan view of the cab; and,

FIG. 6 is a top plan view of the cab.

The broken lines shown in FIG. 2 are for illustrative purposes only and form no part of the claimed design.
